(57) **CLAIM**

The ornamental design for a wrist-mounted light, as shown and described.

DESCRIPTION

FIG. 1 is a front elevation view of a wrist-mounted light showing my new design;

FIG. 2 is a rear elevation view thereof;

FIG. 3 is a right side elevation view thereof;

FIG. 4 is a left side elevation view thereof;

FIG. 5 is a top plan view thereof;

FIG. 6 is a bottom plan view thereof; and,

FIG. 7 is an isometric view thereof.

The broken lines in FIGS. 1 and 7 of the drawings depict environmental subject matter only and form no part of the claimed design.

1 Claim, 3 Drawing Sheets

FIG. 5

FIG. 6

FIG. 7
